(57) **CLAIM**

The ornamental design for a front combination lamp for automobile, as shown and described.

DESCRIPTION

FIG. 1 is a perspective view from the front right side of a front combination lamp for automobile.

FIG. 2 is a perspective view from the front left side thereof.

FIG. 3 is a front elevation view thereof.

FIG. 4 is a right side elevation view thereof; and,

FIG. 5 is a top plan view thereof.

The portions of the front combination lamp shown in broken lines are for the purpose of showing environmental structure only and form no part of the claimed design.
